BRICK HANDLING MECHANISM

Application filed March 8, 1930. Serial No. 434,429.

This invention relates to a brick handling mechanism.

The primary objects of the present invention are to improve the construction and mode of operation of brick handling mechanisms and to produce a brick handling mechanism which will handle brick in large quantities more efficiently than the mechanisms heretofore produced.

10 With the above and other objects in view, the invention consists in a brick handling mechanism embodying the novel and improved features, constructions and combinations of parts hereinafter described and 15 pointed out in the claims, the advantages of which will be readily understood and appreciated by those skilled in the art.

The invention will be readily understood from the accompanying drawings illustrating the invention in its preferred form and the following detailed description of the constructions therein shown.

In the drawings:

Fig. 1 is a view in side elevation illustrating a brick handling mechanism embodying certain features of the invention;

Fig. 2 is a view in front elevation of the mechanism shown in Fig. 1;

Fig. 3 is a view in side elevation illustrating a mechanism embodying certain features of the invention in modified form;

Fig. 4 is a perspective view illustrating a portion of the structure shown in Fig. 3;

Fig. 5 is a view in side elevation illustrating certain features of the invention in still further modified form; and

Fig. 6 is a perspective view illustrating a portion of the structure shown in Fig. 5.

The invention as illustrated is embodied in 40 a brick handling mechanism of the general type particularly adapted for handling units each consisting of a large number of bricks placed in stacked relation.

In the construction shown in the drawings 45 the brick handling mechanism comprises a carrier for lifting a relatively large quantity of bricks and for transporting them from one place to another. This carrier is mounted for vertical movements to raise and lower 50 a load of bricks and also for horizontal move-

ment, and to this end the carrier may be mounted upon the usual crane or other suitable supporting mechanism.

The carrier illustrated in the drawings comprises a frame having a series of parallel horizontal bars 2 at the upper part thereof, a series of depending vertical bars 4, a cross beam 6 connecting the bars 2, an angle plate 8 extending transversely of and connecting the horizontal bars 2 and the upright bars 4, a plate 10 and angle bars 12 and 13 extending transversely of and connecting the lower ends of the upright bars 4, and bracing plates 14 all of which are securely welded, bolted or riveted together to form a strong frame. 60 The frame is adapted to be suspended from a crane or other suitable supporting mechanism by means of hooks 16 engaging in openings in plates 18 and 20 secured to the frame. 65

A series of brick supporting fingers or fork tines 22 are pivoted at 23 to brackets 24 secured to the angle bar 12, as shown in Fig. 2. These fingers are arranged to be inserted in the spaces left between the bricks of certain courses laid in stacked relation in the manner usual in brick handling mechanisms of this character. The fingers 22 are pivoted in definite predetermined spaced relation upon the angle bar 12 and are secured rigidly together in such spaced relation. In the construction 75 shown the fingers are secured rigidly together between their pivotal points and the ends of said fingers by means of an angle bar 26 extending across the several fingers above the same to which the fingers are preferably welded. The fingers may be further secured 80 to the angle bar by means of U-bolts 27 respectively embracing the fingers and passing through the lower side plate of the angle bar 12, as shown in Fig. 2. 90

In the present construction the fingers 22 are held in elevated position substantially at right angles to the upright bars 4, to support and carry a stack of bricks by supporting devices acting on said fingers between the 95 pivotal points thereof and the free ends of said fingers. These supporting devices comprise a series of supporting bars 28 each pivoted at its lower end at 30 to an angle bracket 32 attached to the angle bar 26. From their 100

pivotal points the supporting bars 28 extend upwardly in substantially parallel relation, and adjacent their upper ends these bars pass through U-shaped guide members 34 attached to the horizontal bars 2 and also engage a transverse angle bar 36 secured to the horizontal bars 2 of the frame, as shown in Fig. 1.

In order to hold the brick supporting fingers in horizontal position, the supporting bars 28 are latched in their upper positions shown in Fig. 1. The latch mechanism comprises a transverse rock shaft 38 mounted to turn in bearing blocks 40 attached to the supporting frame. This shaft carries a series of latch fingers or dogs 42 each of which is arranged to engage in a notch 44 in the corresponding supporting bar 28. The rock shaft 38 is yieldingly actuated to engage the dogs 42 in the respective notches in the supporting bars 28 by means of one or more coiled springs 46 each connected at one end to an arm 48 projecting from the rock shaft and at the other end to a point on the frame. The rock shaft 38 is turned in a direction to disengage the dogs 42 from the notches in the supporting bars by means of a cable or chain 50 attached at one end to an arm 52 secured to the rock shaft. The dogs 42 and the notches 44 in the supporting bars are preferably shaped so that when the dogs are engaged in said notches and a stack of brick is supported upon the fingers 22, the friction between the ends of the dogs and the contacting faces of the notches will prevent the disengagement of the dogs from the notches until the load upon the supporting bars 28 is relieved. This will prevent the accidental release of the load of bricks carried by the fingers until the fingers are brought into engagement with the horizontal support upon which the bricks are to be placed by the descent of the carrier.

In order that the fingers 22 may be swung upwardly to a slight degree with relation to the frame when the fingers engage the support upon which the bricks are to be placed, the fingers are preferably made somewhat wider adjacent their outer ends, as shown in Fig. 1. With this construction when the carrier descends vertically, the wider outer ends of the fingers will first engage the horizontal support, and the further descent of the carrier will then cause the fingers to swing upwardly slightly with relation to the frame thereby relieving the pressure exerted by the bars 28 upon the outer ends of the dogs 42.

Other constructions may be employed for causing the outer ends of the brick supporting fingers to engage first the support. Thus the fingers and the latching mechanism therefor may be so constructed that when the fingers are latched in their upper or brick supporting positions, the angle between the same and the upright bars 4 will be greater than a right

angle. This will cause the fingers to "droop" slightly with relation to the frame when carrying a load of bricks and the outer ends of the fingers will first engage the support upon which the bricks are to be placed.

The bricks are prevented from accidentally engaging between the supporting bars 28 by means of suitable abutments which also serve to limit the movement of the fingers 22 beneath the stacked bricks. One of these abutments consists of one side plate of the angle bar 26. An abutment plate 54 also is attached to the supporting bars 28 preferably by welding the same to the bars, as shown in Fig. 1. The space between the lower edge of the abutment plate 54 and the adjacent side plate of the angle bar 26 is filled by a curved plate 56. This curved plate 56 is attached to the adjacent side plate of the cross bar 26 and may consist of an extension of said side plate. As shown in the drawings, this curved plate is attached to the angle bar 26 by means of attaching plates 57 extending across the joint between the curved plate 56 and the adjacent side plate of the angle bar and welded both to the curved bar and the angle bar. The curved plate 56 is provided with slots 58 to receive the supporting bars 28 thereby forming the curved plate with portions projecting between the supporting bars, as shown in Fig. 2. The curved formation of the plate 56 prevents the bricks from becoming displaced between the same and the supporting bars 28 when the fingers 22 are in lowered position, as shown in dotted lines in Fig. 1.

The construction shown in Figs. 3 and 4 is substantially the same as that shown in Figs. 1 and 2 except that the supporting bars 28 are connected in a somewhat different manner to the fingers 22, and a different construction is provided for preventing the bricks from passing between the supporting bars. In the construction shown in Figs. 3 and 4 the supporting bars 28 are connected in spaced relation by means of an abutment plate 60 to which the bars are preferably welded. The bars are pivotally connected at 62 to the fingers 22 by means of a hinge 64 one member of which is secured to the abutment plate 60 and the other member of which is secured to the angle bar 26. In this construction the abutment plate 60 and the adjacent side plate of the angle bar 26 are arranged sufficiently close together to prevent the engagement of bricks between the same.

The construction shown in Figs. 5 and 6 is similar to that shown in Figs. 1 to 4, inclusive, except that the supporting bars 28 are connected in a different manner with the fingers 22 and that a different construction is employed for holding said bars in elevated positions. In the construction shown in Figs. 5 and 6 the bars 28 are connected by

an abutment plate 66 secured to said bars. The bars are pivotally connected at 68 with the fingers 22 by means of a hinge comprising hinge plates 70 and 72. The hinge plate 72 preferably extends across the several fingers 22 and is connected to each finger by means of angle brackets 76. The hinge plate 70 preferably extends across the several supporting bars 28 and is secured to each of said bars, as shown in Fig. 5. The abutment plate 66 and the hinge plate 70 prevent the passage of the bricks between these supporting bars.

The supporting bars 28 are respectively provided at their upper ends with a projection 78 arranged to engage the upper edge of the vertical side plate of the angle bar 36 which extends across and is secured to the horizontal bars 2 of the frame. The position of each of the supporting bars 28 is controlled by means of a bar 80 having therein a series of slots 82 through which the supporting bars 28 project. The controlling bar 80 is carried by arms 84 secured to the rock shaft 86 mounted in bearing blocks 88 secured to the frame. With this construction, upon turning the rock shaft 86 to the right, Fig. 6, the supporting bars 28 will be moved in a direction to disengage the projection 78 from the angle bar 36 thereby releasing the supporting bars and the fingers 22. To the rock shaft is attached an arm 90 to which is connected a cord or cable 92 for actuating the rock shaft in a direction to disengage the projection 78 from the angle bar 36. The rock shaft is actuated in the reverse direction to restore the supporting bars to positions to place the projection 78 above the upper edge of the angle bar 36 by means of a coiled compression spring 94 interposed between the arm 90 and the frame.

It is to be understood that the invention is not limited to the particular construction and arrangement of parts of the illustrated embodiment of the invention but that the invention may be embodied in other forms within the scope of the claims.

Having explained the nature and object of the invention and having specifically described a mechanism embodying the invention in its preferred form, what is claimed is:

1. A brick handling mechanism comprising in combination a frame, devices for supporting the bricks pivotally mounted on said frame, vertically extending supporting bars pivotally connected at their lower ends with said devices between the pivots of the devices and the free ends thereof for supporting the devices, and an abutment plate for preventing the bricks from passing between said bars.

2. A brick handling mechanism comprising in combination a frame, brick supporting devices pivotally mounted on said frame, supporting bars connected with said devices

between the pivots and the free ends thereof and means for preventing the passage of bricks between the bars.

3. A brick handling mechanism comprising in combination a frame, devices for supporting bricks pivotally mounted on said frame, supporting bars for releasably supporting the devices connected with said devices between the pivot and the brick supporting portions thereof, and means for preventing the passage of bricks between the bars.

4. A brick handling mechanism comprising in combination a frame, devices for supporting bricks pivotally mounted on said frame, means for releasably supporting the devices between the pivots and the free ends thereof.

5. A brick handling mechanism comprising in combination a frame, a series of brick supporting devices carried by said frame and mounted for angular movement with relation thereto, supporting bars for supporting said devices connected with said devices between the axis of angular movement and the brick supporting portions thereof, and means for limiting the position of the bricks with relation to said bars.

6. A brick handling mechanism comprising in combination a frame, brick supporting devices carried by said frame and arranged for angular movement with relation to the frame, supporting bars for supporting the devices connected with said devices between the axis of angular movement and the brick supporting portions thereof, and means for preventing the passage of bricks between the bars, both when the devices are in raised positions and when they are in lowered positions.

7. A brick handling mechanism comprising in combination a frame, brick supporting devices supported on said frame and arranged for angular movement with relation to the frame, means for supporting the devices comprising a bar longitudinally movable downwardly in dumping the brick, and means for latching the bar against longitudinal movement downwardly.

8. A brick handling mechanism comprising in combination a frame, brick supporting devices pivoted on said frame, and means for supporting the devices comprising a longitudinally movable bar pivotally connected with the devices at a point between the pivot of said devices and the free ends thereof, and means for latching the bar against longitudinal movement to support the devices.

9. A brick handling mechanism comprising in combination a frame, brick supporting devices mounted on said frame and arranged for movement with relation to the frame to release the bricks, and means for holding said devices in brick supporting

positions constructed to prevent the accidental release of said devices.

10. A brick handling mechanism comprising in combination a frame, brick supporting devices carried on said frame and arranged for movement with relation to the frame to release the bricks, and means for holding said devices in brick supporting position arranged to exert a strong resistance to the release of said devices until said devices engage a support during the descending movement of the frame.

11. A brick handling mechanism comprising in combination a frame, brick supporting fingers pivotally mounted on said frame, and means for rigidly connecting said fingers between the pivots and the free ends thereof.

12. A brick handling mechanism comprising a frame, brick supporting devices pivotally mounted on said frame, means connected with said supporting devices between the pivot and the brick supporting portion thereof for supporting the said devices, and mechanism for releasably holding said means.

Signed at Poughkeepsie this 3rd day of March, 1930.
